ATTORNEY

UNITED STATES PATENT OFFICE.

JOHN MARSHALL, OF FALL RIVER, MASSACHUSETTS, ASSIGNOR TO JAMES MARSHALL & BROTHERS, OF SAME PLACE.

HAT-CLEARING MACHINE.

SPECIFICATION forming part of Letters Patent No. 653,356, dated July 10, 1900.

Application filed January 22, 1900. Serial No. 2,355. (No model.)

To all whom it may concern:

Be it known that I, JOHN MARSHALL, a citizen of the United States, residing at Fall River, in the county of Bristol and State of Massachusetts, have invented certain new and useful Improvements in Machines for Clearing Hats; and I do hereby declare the following to be a full, clear, and exact description of the invention, such as will enable others skilled in the art to which it appertains to make and use the same.

My invention has reference to certain improvements relating to machines for clearing hats, or, in other words, for removing all surfaces stiffening compound from the hats.

The object of my invention is to provide a machine which shall automatically and more efficiently perform that which has hitherto been performed by hand and to make the work more uniform and thorough in every respect.

In the accompanying drawings, which form a part of this application, Figure 1 is an elevation illustrating my improvement; Fig. 2, a broken section at the line xx of Fig. 1, and Fig. 3 a detail detached view illustrating the positions of the brush and sprinkling-pipe with respect to the revolving cone.

Similar numbers of reference denote like parts in all the figures of the drawings.

1 is the frame of the machine; 2, a vertical shaft journaled in the bed of the frame; 3, the hat-supporting cone carried by the upper end of this shaft, and 4 a bevel-gear carried by the lower end of said shaft.

5 is a horizontal shaft journaled in the side of the frame and having mounted on its inner end a bevel-gear 6, meshing with the gear 4, while the outer end of this shaft carries tight and loose pulleys 7 8, respectively.

9 is any suitable scraper-finger secured to the bed of the frame and lying close to the cone 3, the function of this finger being to keep the hats from sticking to the cone.

45 10 is an elevated tank containing a proper solution, such as soda, and 11 is a pipe leading from the bottom of this tank down in close proximity to the cone.

12 is any suitable valve operated by a hand-lever 13, whereby the pipe may be opened or

closed, according as the solution in the tank is required or not.

14 is a pipe leading from any suitable hot-water source and communicating with the pipe 11. In this pipe 14 is any suitable valve 55 15, adapted to be opened or closed by means of suitable and ordinary connections with a treadle 16. In the drawings I have shown a bar 17, loosely connected at one end by means of a link 18 to the side of the pipe, while the 60 outer end of this bar is connected by a pitman-rod 19 with the treadle, the stem of the valve being pivoted to the bar itself.

The lower extremity of the pipe 11 is closed, and this portion of the pipe extends at an angle in parallelism with the face of the cone and is provided with perforations 20, directed toward the cone.

The hat is placed upon the cone over the finger 9, and as the cone revolves the workman operates the valve 12 to permit the soda solution to be discharged against the hat until the latter has become cleared of the surplus stiffening compound. The workman then closes the valve 12, thereby cutting off 75 the supply of soda solution, and with his foot operates the treadle to open the valve 15 and allow the hot water to be discharged through the pipe 11 against the hat, thereby washing the same thoroughly. During the discharge 80 of the soda solution and hot water against the hat the workman employs any suitable brush 21, which is conformed to the shape of the cone, and by pressing this brush against the hat thoroughly scrubs the same as it becomes softened up by the action of the liquids before mentioned.

Of course there are very many details of construction as to the arrangement of the pipes and the structure of the valves in which 90 changes could be made without departing from the spirit of my invention, and I therefore do not wish to be limited in this respect, since I am the first to ever provide a machine for effecting the operation of clearing hats. 95

I have employed a scraper-finger in close proximity to the cone; but I do not wish to be understood as making any claim to such construction, since I am aware that the same has been heretofore employed in the con- 100

struction of hat-stiffening machines, the gist of my invention resting in the provision of the specific construction heretofore described for the purpose of cleansing the hat of the surplus stiffening compound.

Having thus described my invention, what I claim as new, and desire to secure by Letters Patent, is—

1. In a machine for clearing hats, the combination of a rotary cone, a scraper-finger extending close to said cone, suitable pipes leading from a soda solution and hot water in close proximity to said cone and perforated opposite the cone and valves and suitably-operated means whereby said solution and hot water are discharged at will against the hats, substantially as set forth.

2. In a machine for clearing hats, the com-

bination of a rotary cone, a pipe leading from a soda-solution supply and having its lower extremity perforated and extending in proximity to said cone, a pipe leading from a hot-water supply and communicating with the first-mentioned pipe, suitable valves in each of said pipes, and independent means for operating said valves whereby the soda solution or the hot water may be discharged against the hats as desired, substantially as shown and described.

In testimony whereof I affix my signature in presence of two witnesses.

JOHN MARSHALL.
